RALPH H. WOLFE AND MAMIE WOLFE, OF KANSAS CITY, MISSOURI, ASSIGNEES OF
ONE-HALF TO JOHN M. LLOYD, OF INDEPENDENCE, MISSOURI

UNIFORM

Application filed December 19, 1928. Serial No. 327,134.

Our invention relates to garments and more particularly to covering garments such as uniforms, smock frocks, house dresses and the like, the principal objects of the invention being to adapt a garment of this character for fitting any figure and to hang in straight vertical lines when adjusted, and to provide a garment that can be fitted and fastened without the use of buttons, snaps or like devices.

Ordinary covering garments, for example, coat-like smocks open from top to bottom, are adjusted to the wearer's size by moving one vertical edge over the other in overlapping relation and the edges tend to separate and may be accidentally separated to expose the dress or knees.

Tubular garments are ordinarily made to measure for neat fitting and if adjusted to fit a smaller figure tend to be wrinkled and irregularly folded, for example when compressed by a belt, and are therefore both uncomfortable and relatively unsightly. Furthermore, it is difficult to cause a garment not made to exact measure, or one made large enough to put on easily, to hang in straight lines as desired.

Further objects of our invention therefore, are to provide a garment of the type indicated that will cover the knees of the wearer when seated, to adapt a tubular garment for fitting any form, to facilitate the putting on and adjustment of a covering garment having a tubular portion and to provide a tubular garment that when adjusted to fit the wearer will hang in straight vertical lines, whereby the garment may be worn as a dress.

In accomplishing these and other objects of the invention, we have provided improved details of structure, the preferred forms of which are illustrated in the accompanying drawings, wherein:

Fig. 1 is a perspective view of a garment constructed in accordance with our invention illustrated in adjusted position to fit the figure of the wearer.

Fig. 2 is a perspective view of the garment in spread position disclosing particularly the tubular skirt, spaced waist portions, and manner of attaching the ties.

Fig. 3 is a cross section of the skirt of the garment in position shown in Fig. 1.

Referring in detail to the drawings:

1 designates a tubular skirt of our improved garment having a closed front and 55 2 a waist having vertical edges 3 and 4 forming the opening front of the garment and preferably integral with the skirt, and having shoulder portions 5 for supporting the garment from the shoulders of the wearer.

The garment is adapted to be stepped into or to be put on over the head, and the skirt is therefore made relatively large circumferentially to facilitate the process and for convenience in walking or sitting.

The skirt is folded on vertical lines 6 and 7 but in opposite directions to define a panel 8, the folding providing a pleat adapted normally to lie with the fold edge 6 exposed and the inner fold edge 7 concealed by the overlying panel and portion of the skirt adjacent the edge 6.

We further particularly provide for the spacing of the vertical edges 3 and 4 of the waist, and alignment of the edges respectively 75 with the fold edges 6 and 7 of the skirt.

The vertical edges of the waist therefore are spaced substantially by the width of the panel to provide a relatively wide open front when the garment is in loose position and the panel 70 of the skirt is outspread, thus facilitating the putting on of the garment, and providing for fitting a garment to different figures.

One lateral end of the upper edge 9 of the skirt panel is tacked to the adjacent skirt portion to define the fold edge 6 in alignment with and constituting a continuation of the edge 3 comprising the fold edge of the waist hem 10, as indicated at 11. The tacking 11 preferably comprises a transverse continuation of the vertical line of stitching 12 whereby the hem 10 is formed. The opposite waist edge 4 is a fold edge of a hem, but the adjacent portion of the panel is preferably not tacked to the skirt. Ties 13 and 14 are attached to the garment preferably at the upper edges of the skirt panel and on the hems of the waist as indicated at 13' and 14' for drawing the edges of the waist in opposite directions and fitting the garment to the wearer.

Our invention is particularly applicable to garments having darts 15 formed and positioned as illustrated in Fig. 2, which may comprise folded front portions of the waist forming darts tapering downwardly from the shoulders to points 16, the position and shape of the darts contributing to the ability of the garment to hang in vertical lines.

The garment is provided with a slot 17 positioned adjacent the edge 3 of the waist which is aligned with the outside fold edge 6 of the skirt, and the tie 13 attached to the opposite edge 4 of the waist is extended through the slot whereby the inner fold of 15 the skirt panel may be drawn under the outer fold while the outer fold is being drawn in the opposite direction coincidentally with drawing the waist portions into position.

Particular attention is called to the formation of a permanent fold line, preferably by tacking one upper corner of the panel to the skirt, and the alignment of the vertical edges of the waist with the fold edges of the panel, whereby permanent vertical lines from top 25 to bottom of the garment are provided for, the aligned edges 3 and 6 of the waist and skirt always hanging vertically.

Garments of the character described may be provided in a relatively small number of 30 sizes. A garment may be put on easily, because of the relatively large tubular skirt and the open waist. The tie 13 is passed through the slot, the two ties extended around the person and drawn sufficiently to cause the 35 waist portion to fit the person, and then tied.

The drawing of the waist edges into overlapping relation will incidentally cause the corresponding folded edge portions of the skirt to move into similar overlapping relation, the panel itself being loosely folded in the process to take up the slack.

The folds that result from adjustment of the panel, are concealed by the portion of the skirt adjacent the edge 6, and lie in vertical 45 lines, and do not disturb the lines of the waist.

The aligned edges of the waist and skirt pleat always hang vertically, and the skirt is always closed to prevent exposure of the 50 dress or person of the wearer. The lower portion of the skirt may be spread, due to the excess breadth comprised in the pleat.

The provision of the darts as shown enables the waist to hang in vertical lines from the 55 shoulders, and the relation of the tubular skirt to the waist provides for the symmetrical cal suspension of the entire garment.

It is apparent that the overlapping of the 60 waist portions and method of attaching the ties, provide for neatly fitting the garment to the wearer, and fastening it securely without the use of buttons, snaps or like fasteners.

A garment constructed as described may be 65 put on over the head, or may be stepped into.

What we claim and desire to secure by Letters Patent is:

1. In a garment of the character described, a closed tubular skirt portion folded on spaced vertical lines, a waist portion having vertical edges forming a front opening and aligned with said fold lines, and means including ties having ends attached to the garment at said lines for fitting the garment to the wearer.

2. In a garment of the character described, a skirt portion having a closed front, a waist portion having vertical edges forming a front opening, the skirt being adapted to be folded on vertical lines aligned with the vertical edges of the waist to form a front panel, and means attaching a portion of the panel to an adjacent portion of the skirt to define one of said vertical lines, said attaching means being limited to the waist line of the skirt.

3. In a garment of the character described, a skirt having a closed front and inner and outer single folds defining fold edges of a vertical panel, a waist attached to the skirt with vertical edges substantially aligned with the fold edges, and ties attached to the garment at the waist line thereof in alignment with the edges of said panel for effecting folding of the skirt on the lines defined by said fold edges.

4. In a garment of the character described, a skirt portion having a closed front and a vertical fold defining an edge of a front panel, and a waist having vertical edges spaced to form a front opening and for alignment of one edge with the edge of said fold, the other of said waist edges defining the opposite edge of the skirt panel, and means attaching the upper edge of the panel to the adjacent skirt portion, said means being limited to the lateral end portion of the upper edge portion of the panel adjacent the fold edge thereof for the purpose described.

5. In a garment of the character described, a tubular skirt having a pair of oppositely formed folds forming a vertical panel, an open-front waist having circumferential length less than the circumference of the skirt for spacing the vertical free edges of the waist when the panel is extended laterally, the vertical edges of the waist being aligned with the vertical fold edges of the panel, and ties having ends attached to the garment at said aligned vertical edges of the waist and skirt folds for moving said edges circumferentially to adjust the garment to the wearer, said folds being free to open.

6. In a garment of the character described, a waist having vertical spaced edges forming a front opening, a skirt having a closed front including a panel-like portion having approximately the width of the waist opening, the front of the garment being folded to form a vertical fold edge extending from the bottom edge of the skirt upwardly along one of

the waist edges, the waist portion of said fold being stitched to the waist to form a hem, the skirt portion of the fold being left free to open, the waist having a slot adjacent said hem, and ties including a tie attached to one edge of the waist for extending through said slot, and a tie attached to said hem for drawing the fold edge across the garment to form vertical folds in the skirt panel portion for fitting the garment to the wearer.

7. In a garment of the character described, a closed tubular skirt portion including a vertical fold, a portion of the fold at the upper edge thereof being tacked to the skirt, leaving the major portion of the fold free to open, a waist having normally spaced vertical edges forming an open front and provided with a slot, and ties having ends fixed respectively to the edges of the waist, one of said ties extending through said slot.

20 In testimony whereof we affix our signatures.
